FIG -1

FIG-2

FIG-3

FIG-4

Fig. 1 is a side elevational view of a resuscitator for applying artificial respiration, showing my new design;

Fig. 2 is a fragmentary front perspective view taken from the opposite side thereof, showing the mouthpiece;

Fig. 3 is a fragmentary rear perspective view thereof showing the valve housing; and

Fig. 4 is a fragmentary front perspective view thereof showing the valve housing slightly rotated in clockwise direction.

The dominant features of my design reside in the full-line portions of the drawing.

I claim:

The ornamental design for a resuscitator for applying artificial respiration, as shown and described.
